CLAIM

The ornamental design for an ice scraper, as shown and described.

DESCRIPTION

FIG. 1 is a front perspective view for an ice scraper showing our new design;

FIG. 2 is a front elevational view;

FIG. 3 is a rear elevational view;

FIG. 4 is a first side elevational view;

FIG. 5 is a second side elevational view;

FIG. 6 is a bottom plan view;

FIG. 7 is a top plan view; and,

FIG. 8 is a front plan view including a specific car design. The broken line showing of a car in FIGS. 1 through 6 is for illustrative purposes only and forms no part of the claimed design.
